(57) **CLAIM**

The ornamental design for a hollow screw, as shown and described.

DESCRIPTION

FIG. 1 is a perspective view showing the front, top and left sides of the hollow screw;

FIG. 2 is a front elevation view of the hollow screw;

FIG. 3 is a rear elevation view of the hollow screw;

FIG. 4 is a right side elevation view of the hollow screw;

FIG. 5 is a left side elevation view of the hollow screw;

FIG. 6 is a top plan view of the hollow screw; and,

FIG. 7 is a bottom plan view of the hollow screw.

The broken lines in the drawings illustrate portions of the hollow screw and form no part of the claimed design.

The depth of the internal bottom surface of the hollow shaft forms no part of the claimed design.
